UNITED STATES PATENT OFFICE.

JOHN MAROLD, OF MADISON, ILLINOIS.

CAR-ROOF.

959,366.

Specification of Letters Patent. Patented May 24, 1910.

Application filed January 28, 1910. Serial No. 540,623.

To all whom it may concern:

Be it known that I, JOHN MAROLD, a citizen of the United States, residing at Madison, in the county of Madison and State of Illinois, have invented new and useful Improvements in Car-Roofs, of which the following is a specification.

This invention relates to improvements in car roofs and has for its object the provision of a device of that kind comprising a plurality of metal sheets so constructed that they will not be displaced or sprung by the vibration of the car to which they are applied.

Another object is the provision of a locking member for securing the sheets together whereby the usual method of employing boards and nails to secure the sheets to the car will be dispensed with.

With these and other objects in view as will more fully hereinafter appear, the present invention consists in certain novel details of construction and arrangement of parts hereinafter to be more fully described, illustrated in the accompanying drawings and more particularly pointed out in the appended claims; it being understood that various changes in the form, proportion, size and minor details of the device may be made, within the scope of the appended claims, without departing from the spirit or sacrificing any of the advantages of the present invention.

In the accompanying drawings forming a part of the specification: Figure 1 is a plan view of a car roof showing my improved device applied thereto. Fig. 2 is an end view of the upper end portion of a car and showing the sheets in end elevation and the cap plate for covering the said sheets. Fig. 3 is a vertical sectional view approximately on the line 3—3 of Fig. 1. Fig. 4 is a detail perspective of one of the sheets. Fig. 5 is a similar view of the locking member.

The body of the car is designated by the numeral 5, the sheath roofing by the numeral 6, the eaves by the numeral 7 and the ridge by the numeral 8. Since these parts are all of well known construction a detailed description of the same will not be given.

The construction forming a part of the subject-matter of the present invention comprises a plurality of plates designated in general by the numeral 9. Since these plates are all of identical structure a detailed de-

scription of one will suffice:—By reference now to the drawings, it will be seen that the sheets are arranged transverse the roof 5 and extend from points adjacent to the ridge 8, to the eaves 7. The sheets may be of any desired width and are preferably of sheet iron or analogous material. By reference to the drawings it will be seen that each plate has its marginal sides bent over one face of the sheet as shown at 10 and 11. These bent portions constitute locking tongues to engage with a locking member to be presently described. The outer ends of the plates are bent downwardly and are secured to the eaves 7 by nails or the like, while the inner ends of the plates are bent upwardly and at right angles and extend to points adjacent to the ridge 8.

What will subsequently be termed a locking member is designated in general by the numeral 12. This member is formed of a single piece of sheet metal corresponding approximately in length to the length of the sheets but considerably less in width than the width of said sheets. The inner end portion of the locking member 12 is reduced in width and bent upwardly as shown at 13 whereby a tongue is formed, and portions adjacent to the longitudinal edges of the locking member are bent over one face of the latter as shown at 14 and 15. The bent portions 14 and 15 are designed to engage with the marginal bent portions of two adjacent sheets and when so positioned will operate to firmly clamp said sheets together. The outer end portions of the locking members are bent downwardly and secured to the eaves 7 similar to the sheets 9. It will be evident that when the locking member 12 engages with two adjacent sheets that the tongue 13 will bear on the upwardly bent inner end portions of two adjacent sheets and when so bearing will be secured by means of an auxiliary locking member 16. The locking member 16 is of a length corresponding to the width of the upwardly bent inner end of each sheet and has its marginal sides bent over one face and spaced sufficiently far from the said face to receive the tongue 13 whereby the latter will be clamped to the said upwardly bent inner ends of the sheets.

It will be evident when the sheets are secured by the locking members that the major portion of each sheet will not be rigidly secured to the roof sheathing thus per-

mitting more or less movement of the entire number of sheets when the car is rounding curves whereby the usual warp of the car top will be prevented.

5. In order to provide a covering for the adjacent ends of the sheets I provide a cap plate designated in general by the numeral 17. This member is preferably formed of sheet metal and is designed to house the 10 ridge 8. Portions adjacent to the opposite longitudinal sides of the cap plate are bent downwardly and at right angles as shown at 19 and 20, these downwardly bent portions bearing on the sheets and locking members 15 at points outwardly from the locking tongues 13. The opposite end portions of the cap plate are bent downwardly and secured to the opposite ends of the ridge 8. With this construction it will be manifest 20 that the adjacent ends of the sheets will be covered and it will be further observed owing to the construction of the marginal sides of the locking members and sheets, that a tight joint will be produced which 25 will prevent the entrance of water.

From the foregoing it can be seen that I have provided a device which is simple in structure and inexpensive to manufacture which may be applied to box cars, coaches, 30 or in fact all rolling stock for railroads in which the object is provided with a roof.

Having thus described the invention, what is claimed is—

1. A car roof comprising a plurality of 35 sheets having their outer ends secured to the eaves and their inner ends upturned and ar-

ranged adjacent to the ridge, each of said sheets having similarly rebent side margins, and a locking strip having side margins bent over one of its faces to receive the bent 40 portions of the sheets, and a cap plate secured to the ridge and extending throughout the length of the roof and having downwardly bent side portions to bear on the said locking strips at points adjacent to the 45 upturned inner ends of the sheets.

2. A car roof comprising a plurality of sheets having their outer ends secured to the eaves and their inner ends upturned and arranged adjacent to the ridge, each of said 50 sheets having similarly rebent side margins, and a locking strip having side margins bent over one of its faces to receive the bent portions of the sheets and terminating at its inner end in an upwardly extending tongue 55 to bear on the upturned inner ends of two adjacent sheets, an auxiliary locking member having similarly rebent side margins to receive the said locking tongue and the rebent sides of the upturned inner ends of 60 two adjacent sheets, and a cap plate secured to the ridge and extending throughout the length of the roof and having downwardly bent side portions to bear on the said locking strips at points in advance of the said 65 tongues.

In testimony whereof I affix my signature in presence of two witnesses.

JOHN MAROLD.
